UNITED STATES PATENT OFFICE

2,509,291

ATOMIZER

Paul Engstrum, Washington, D. C., assignor to
Air-O-Spra Corporation, a corporation of Delaware

Application March 18, 1947, Serial No. 735,386

2 Claims. (Cl. 299—88)

1

This invention relates to atomizers. The invention is more particularly concerned with an atomizer head of a different and improved construction over that disclosed in my co-pending application, Serial No. 731,458, filed February 28, 1947.

A primary object of the invention is the provision in a cylindrical spray head having cooperating atomizing ports disposed below the free end of the head, of a passage in the head permitting unobstructed communication of the ports with the atmosphere for providing a conical-shaped spray of relatively uniform density.

A further, and more specific, object of the invention is the provision in a cylindrical spray head, of a diametrical passage therein adjacent its outer end but spaced therefrom by a relatively thin outer wall, there being cooperating atomizing ports adjacent the bottom of the passage and axially of the cylindrical head, the wall being provided with a circular aperture for propulsion therethrough of a spray from the ports.

Additional objects and advantages of the invention will become apparent in the course of the following detailed description, taken in connection with the accompanying drawing, wherein:

Figure 1 is a top plan view of the spray head.

Fig. 2 is a vertical axial section in the plane of line 2—2 on Fig. 1.

Fig. 3 is a broken side elevational view, on a reduced scale, showing the cooperating telescoping tubular members for producing the spray, the upper of such tubular members being provided with the head, with which the present invention is concerned.

The head 10 is provided with a tubular skirt 11, with which cooperates a tubular slide member 12 which is indicated only fragmentally and which forms no part of the present invention.

A liquid-supporting tank 13 is disposed coaxially of the head 10 and has a screw-thread connection 14 with the head. The head 10 is provided with a port or aperture 15 whose lower end communicates with the upper end of the tank 13 and whose upper end is normally closed by a plug 17 having a screw-thread connection with the head, and a sealing gasket 18 interposed between the plug and a shoulder 19 at the upper end of port 15. The removable plug 17 provides for admission of spray liquid into tank 13.

An air tube 21 extends axially of head 10 and has a screw-thread connection 22 therewith, the bore of the tube communicating with a recess 23 in the head axially thereof and the upper end of the recess communicating with the lower end

2

of a port 24 of substantially small diameter and whose upper end opens into the bottom of an air passage or opening 25 extending diametrically of the head closely adjacent the upper end thereof, and which will be later more specifically referred to.

An air check valve is disposed within the recess 23, and comprises a ball 26 yieldably urged against the upper end of the air tube by means of a coil 10 spring 27.

A capillary tube 28 has its upper end secured in the head 10 and communicates with the lower end of a port 29 of a diameter substantially equal to that of the bore in the tube.

15 The lower end of the tube 28 is adapted to terminate slightly above the bottom of the tank 13.

20 A push valve assembly 39 is removably disposed within an opening 31 in the head 10, with its axis disposed at right angles to the axis of the head 10. This valve generally comprises a body portion 32 having an axial bore 32^a controlled by a valve 32^b operable by the push head 33, and such bore is in communication with a chamber 34 through ports 32^c and with which chamber the port 29 communicates.

25 The valve further comprises a nozzle 35 having a port 36 whose free end is directly above the air port 24. The port 36 is selectively put into communication with the bore in the body portion upon inward movement of the head 33 which is normally urged outwardly by a spring 33^a to keep the valve closed.

30 The spray S is formed by means of air being forced vertically upwards through port 24 which, by means of differential air pressure, sucks liquid out of port 36 and propels the resulting spray outward, in line with port 24, in conical form and of relatively uniform density.

35 The spray head 10 in accordance with the present invention is provided with an opening or passage 25 which extends diametrically through the head adjacent its upper end. The sides of the passage preferably taper toward the ports 24, 36 from the relatively thin wall 38 at the top thereof, and such wall is provided with a relatively large aperture 39 axially of the head and whose circumferential wall is preferably beveled,

40 as at 40, at the same angle as that of the opposite sides of the passage.

45 The atomizing ports 24, 36 are disposed adjacent the narrow bottom wall of the passage but are not wholly surrounded by walls, in that the opposite ends of the passage 25 are open to the

atmosphere at the level of the ports with an attendant better action of the spraying nozzles.

The spray S is indicated in Fig. 3, wherein it is propelled through the aperture 39 axially of the nozzle 24.

Since the port 36 is carried by the manually operable valve 30 and it has been found most expedient to support the valve in the cylindrical head 10 diametrically thereof, the coating ports 24 and 36 are, as a result thereof, located substantially below the upper end of the head.

With the ports thus disposed, it has been found necessary to admit atmospheric air to the ports as well as to the initially formed spray for proper operation of the device.

It has also been found, through extended experimentation, that openings or passages of any form are not sufficient if the desired conical spray is to be formed by the device. It has still further been found that opposed walls diverging outwardly from the ports were necessary in the provision of the conical spray and that air be admitted to the spray substantially all the way from the ports to the top of the head.

The passage 25 having the opposed outwardly diverging walls and the aperture 39 in the thin wall 38, and with the circumferential wall of the aperture bevelled at the same angle as the passage walls, has been found most effective regardless of what the exact theory or explanation might be.

Thus, as seen in Fig. 3, the opposite sides of the spray S are substantially parallel with the passage walls, and the thin wall 38 prevents downward air currents, but the aperture 39 therein provides for expulsion of the spray. Furthermore, by providing a substantially thin wall, air is admitted laterally substantially from the ports to the top of the head.

In the particular structure disclosed, the passage 25 admits the air while the outwardly diverging walls of the passage determine the form of the spray.

While I have disclosed my invention in accordance with a single specific embodiment thereof, such is to be considered as illustrative only, and not restrictive, the scope of the invention being defined in the subjoined claims.

What I claim and desire to secure by U. S. Letters Patent is:

1. In an atomizer including a cylindrical head, an air passage extending diametrically through the head adjacent the upper end thereof, said passage being defined by opposite side walls extending through the head adjacent and symmetrical to an axial plane thereof, and spaced relatively wide top and relatively narrow bottom walls normal to said plane, said side walls converging from said top wall to said bottom wall, cooperating spray-forming ports, including an air port opening through the narrow bottom wall of the passage axially of the head, a spray liquid port opening through one of said side walls at right angles to the axis of the head and immediately above the air port, and a spray-releasing aperture in the top of said head opening through said wide top wall and being defined by a circular wall.

2. The structure according to claim 1, wherein said circular wall is concentric to the axis of said head and said air port and which is bevelled and tangent to said side walls.

PAUL ENGSTRUM.
